UNITED STATES PATENT OFFICE.

WILLIAM F. SCHMIDT, OF BLANCO, CALIFORNIA.

DESIGN FOR AN EMBROIDERY-THIMBLE.

SPECIFICATION forming part of Design No. 34,156, dated March 5, 1901.

Application filed March 22, 1900. Serial No. 9,811. Term of patent 14 years.

To all whom it may concern:

Be it known that I, WILLIAM F. SCHMIDT, a citizen of the United States, and a resident of Blanco, in the county of Monterey and State 5 of California, have invented and produced a new and original Design for an Embroidery-Thimble, of which the following is a specification, reference being had to the accompanying drawings, forming part thereof.

10 Figure 1 is a plan view of an embroidery-thimble, showing my new design. Fig. 2 is a side elevation thereof. Fig. 3 is an end view of the same.

As shown in the drawings, the leading or 15 material features of my design consist of a body of approximately half-conoidal shape having a clean-cut inner end, a smooth surface, and a longitudinal tapering opening in its upper side gradually flaring from a point

near its rounded tip to the open end of the 20 thimble.

1 is an embroidery-thimble, of approximately half-conoidal form, having a clear-cut open end 2, a rounded tip 3, and a narrow tapering opening 4 in its upper side gradually 25 flaring from a point near the rounded tip to the open end of the thimble.

Having thus described my invention, the following is what I claim as new therein and desire to secure by Letters Patent: 30

The design for an embroidery-thimble, as herein shown and described.

In testimony whereof I affix my signature in presence of two witnesses.

WILLIAM F. SCHMIDT.
